No. 639,425.

Patented Dec. 19, 1899.

S. McGAUGHEY.

BABY CARRIAGE.

(Application filed Oct. 11, 1899.)

(No Model.)

THE NORRIS PETERS CO., PHOTO-LITHO., WASHINGTON, D. C.

UNITED STATES PATENT OFFICE.

SYLVESTER MCGAUGHEY, OF RANDVILLE, MICHIGAN.

BABY-CARRIAGE.

SPECIFICATION forming part of Letters Patent No. 639,425, dated December 19, 1899.

Application filed October 11, 1899. Serial No. 733,284. (No model.)

To all whom it may concern:

Be it known that I, SYLVESTER MCGAUGHEY, residing at Randville, in the county of Dickinson and State of Michigan, have invented 5 certain new and useful improvements in Baby-Carriages, of which the following is a specification.

This invention, while relating to the general structure of baby-carriages and similar manually-propelled carts and other small vehicles, more particularly refers to means whereby the pusher may readily turn the front axle for guiding the carriage without the necessity of tilting the carriage-body or 15 lifting the front wheel from the ground.

My invention comprehends, primarily, a very simple, effective, and conveniently-manipulated means capable of being so arranged that the general structure of the running-gear 20 or body is simplified and capable of being the more economically constructed instead of said construction being increased or rendered the more bulky.

My invention in its subordinate features 25 consists in certain novel and peculiar combination of parts, all of which will be described in detail and then specifically pointed out in the appended claims, reference being had to the accompanying drawings, in which—

30 Figure 1 is a perspective view of a baby-carriage with my improvements attached. Fig. 2 is a similar view illustrating the reach-bar, the axles, and the guiding mechanism in detail. Fig. 3 is a plan view of the parts 35 shown in Fig. 2. Fig. 4 is a cross-section on the line 4 4 of Fig. 2. Fig. 5 is a detail view of the handle-bar and its lock devices, hereinafter referred to.

Referring now to the accompanying drawings, in which like numerals indicate like parts in all the figures, it will be observed that I construct the running-gear of a single reach-bar 1, of hard wood or other suitable material, which extends midway of the carriage, its 45 rear end being bent upward at 1^a to form a handle-post 1^b, upon the upper end of which is centrally pivoted the pusher-bar 2, which extends transversely and has its ends terminating in handholds 2^a.

50 To strengthen the handle-post 2, a stout wire-rod brace 3 connects the angle portion of the reach, as clearly shown in Fig. 2. At

a point a little inward from its outer end the reach-bar has pivotally secured to its under side the top member of a fifth-wheel, said member comprising an apertured disk 4 and shank 4^a, which is secured to the bar 1 by saddle-clips 5, as shown. The said top member is held to engage the bottom member of the fifth-wheel, which consists of an apertured 60 disk 6, having laterally-extending shanks 6^a secured to the top of the front axle 7 by saddle-clips 6^b.

8 indicates the king-pin for the fifth-wheel.

9 indicates the rear axle, which centrally 65 thereof has secured upon its upper face by suitable clips, as shown, a chair-piece 10, having a central transverse seat 10^a to receive the pendent flange member 11, fixedly secured on the under side of the rear axle. 70

It will be understood that when the reach and the axles are of wood the several members constituting the fifth-wheel and the seat connections are of metal; but when the reach and axles are of pieces of metal the several parts 75 referred to are made as integral portions of the said axles and reach.

Upon the upper face and near the spindle ends of the rear axle are fitted triangular-like bearing members 12, one at each end, which 80 are detachably secured to the axle, as shown, said bearings each having an opening or slot 12^a on the outer or apex end, and on the vertical member of each bearing 12 is fitted a guide-pulley 13, the purpose of which will hereinafter appear. 85

So far as described it will be seen that the running-gear of the carriage comprises a single longitudinal reach-bar and two cross-axles. This arrangement provides for a very economical manufacture of the gear and also permits 90 of the ready combining therewith of my form of guide means.

Although I use but a single reach-bar, the carriage-body is supported on the front spring 15, fixedly secured on the extreme front end of the reach-bar and extending transversely thereof, and a pair of rear springs 16 16, one being secured to each end of the rear axle at a point inside the bearings 12, and each spring 100 extends lengthwise of the body. This provides a simple and effective means for supporting the carriage-body and a convenient arranging of the steering devices, which con-

- sist of a pair of cables or chains 18 18, which at a point between the axles are crossed and each of which has a hook 18^a, whereby it can be quickly connected with the eyes or staples 19, one on each end of the front axle, said staples having each an adjusting or wing nut 20, whereby the slack of the chains can be taken up at will. The cables 18 after being crossed pass over the guide-rollers 13, and the ends 10 of said cables then pass up and connect with eyes 21 upon the pusher-handle, the cables secured to the front axle at the left joining with the pusher-bar at the right. As the cables project above a horizontal plane after 15 they leave the pulleys 13, said pulleys are held inclined, as shown, and to facilitate the placing of the cables or chains against the pulleys the bearing members 12 are slotted, as hereinbefore described.
- 20 The pusher-bar 2 is pivotally supported on the handle-post of the reach and is normally held from turning by a suitable lock mechanism, preferably of a construction best shown in Fig. 5, by reference to which it will be seen 25 that the under face of the bar 2 is cut out to form a flat bearing portion that extends to each side of its axial point, said part of the bar 2 being made to engage a flat bearing portion 22, fixedly secured on the upper end of the 30 handle-post, with which the pusher-bar is held normally locked by the spring-actuated latch-lever 23, fulcrumed on the top of the bar 2 and having its handle end 23^a adjacent one of the handholds 2^a, the latch 23^b passing 35 through an aperture 2^c in the bar 2, registering with the aperture 23^d on the member 23.
- Having thus described my invention, what I claim, and desire to secure by Letters Patent, is—
- 40 1. As an improvement in manually-pushed vehicles, a running-gear comprising a central reach-bar the rear end of which bends upward and forms a handle-post; a front axle pivotally secured on the said reach-bar, and a rear 45 axle fixedly secured upon the said reach-bar; a body-bearing spring pivotally mounted transversely on the forward end of the reach; a longitudinally-extending body-bearing spring

mounted on each end of the rear axle; a pusher-bar pivotally mounted upon the upper 50 end of the reach, and cable or chain connections between said pusher-bar and the front axle, said connections extending forwardly in the plane below the spring-bearings.

2. In a child's carriage, the combination 55 with the center reach-bar, the rear end of which terminates in an upwardly-projecting handle-post; of a forward axle pivotally secured on the reach; the rear axle fixedly secured on said reach; a guide on each end of 60 the rear axle; the cables or chains, one of said cables being secured to each end of the front axle, said cables being crossed at a point between the front and rear axles and passed over the guides on the rear axle; the pusher-bar pivotally mounted on the reach-handle post; locking devices holding the pusher-bar normally locked to the handle-post, said bar having its ends mounted on the rear ends of the cables, all being arranged substantially 70 as shown and described.

3. In a vehicle of the class described, a center reach-bar, said bar extending rearward and upward, to form a handle-post; the front axle, said axle and reach-bar having fifth-wheel connections; and an adjusting-eyebolt 75 on each end of the front axle; a rear axle pivotally mounted on the reach; a slotted bearing upon each end of the rear axle carrying a guide-pulley; a pusher-bar axially mounted 80 upon the upper end of the reach-handle post and locking means for holding said bar from turning the cable or chain secured to each end of the said bar, each cable projecting forward parallel with the reach-bar and over the 85 guide-pulley on its corresponding side, said cables crossing at a point between the front and rear axles, said cables having their ends detachably connected with the adjustable eye-bolts, upon the front axle, all being arranged 90 substantially as shown and described.

SYLVESTER McGAUGHEY.
